(57) **CLAIM**

The ornamental design for a building control device, as shown and described.

DESCRIPTION

FIG. 1 is a perspective view of a building control device in accordance with the present invention;

FIG. 2 is a front elevation view of the building control device of FIG. 1;

FIG. 3 is a right side view of the building control device of FIG. 1;

FIG. 4 is a left side view of the building control device of FIG. 1;

FIG. 5 is a top plan view of the building control device of FIG. 1;

FIG. 6 is a bottom plan view of the building control device of FIG. 1;

FIG. 7 is a perspective view of another building control device in accordance with the present invention;

FIG. 8 is a front elevation view of the building control device of FIG. 7;

FIG. 9 is a left side view of the building control device of FIG. 7;

FIG. 10 is a right side view of the building control device of FIG. 7;

FIG. 11 is a top plan view of the building control device of FIG. 7; and,

FIG. 12 is a bottom plan view of the building control device of FIG. 7.

The portions illustrated in broken lines on the figures are for illustrative purposes only and form no part of the claimed design.
